Primary Examiner—M. N. Pandozzi*(74) Attorney, Agent, or Firm*—Marger Johnson & McCollom, P.C.(57) **CLAIM**

The ornamental design for streamlined in-wall coffee maker, as shown and described.

DESCRIPTION

FIG. 1 is a frontal-side perspective view of an in-wall coffee maker embodying the ornamental design of the invention. The features shown in dashed lines are not part of the claimed ornamental design.

FIG. 2 is a top plan view of the coffee maker of FIG. 1.

FIG. 3 is a right side elevation view of the coffee maker of FIG. 1.

FIG. 4 is a front elevation view of the coffee maker of FIG. 1; and,

FIG. 5 is a left side elevation view of the coffee maker of FIG. 1.
